(57) **CLAIM**

The ornamental design for an inhaler as shown and described.

DESCRIPTION

FIG. 1.1 is a front perspective view of the inhaler.

FIG. 1.2 is a back perspective view of the inhaler.

FIG. 1.3 is a right view of the inhaler.

FIG. 1.4 is a left view of the inhaler.

FIG. 1.5 is a top view of the inhaler.

FIG. 1.6 is a bottom view of the inhaler.

FIG. 2.1 is a front view of the inhaler.

FIG. 2.2 is a back view of the inhaler.

FIG. 2.3 is a right view of the inhaler.

FIG. 2.4 is a left view of the inhaler.

FIG. 2.5 is a top view of the inhaler.

FIG. 2.6 is a bottom view of the inhaler.

FIG. 3.1 is a front view of the inhaler.

FIG. 3.2 is a back view of the inhaler.

FIG. 3.3 is a right view of the inhaler.

FIG. 3.4 is a left view of the inhaler.

FIG. 3.5 is a top view of the inhaler.

FIG. 3.6 is a bottom view of the inhaler.

The broken lines in the drawings depict portions of the article that form no part of the claimed design.

1 Claim, 18 Drawing Sheets
